BY Victor J. Evans

WITNESS:

ATTORNEY

UNITED STATES PATENT OFFICE.

ROY E. WOLTKAMP, OF KANSAS CITY, KANSAS.

SPRING-RETAINING DEVICE.

Application filed January 3, 1923. Serial No. 610,480.

To all whom it may concern:

Be it known that I, ROY E. WOLTKAMP, a citizen of the United States, residing at Kansas City, in the county of Wyandotte and State of Kansas, have invented new and useful Improvements in Spring-Retaining Devices, of which the following is a specification.

This invention relates to a spring retaining device, the general object of the invention being to provide means whereby the device can be easily and quickly placed upon a valve stem or removed therefrom and the parts of which are permanently fastened together so that there is no danger of losing or misplacing a part.

Another object of the invention is to so form the device that the wear of the spring is equalized.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a fragmentary sectional view through part of an internal combustion motor showing the invention in use.

Figures 2 and 3 are detail views of the device itself.

In these views 1 indicates a part of the cylinder head, 2 the valve stem, 3 the guide of the same and 4 the spring. The improved device is shown at 5 and consists of a circular member composed of two halves, each half having a pair of ears 6 thereon which are pivoted together by the pins 7 so that the two halves are hingedly connected together.

Each half has a semi-circular notch 8 in its

inner edge which forms a central opening for receiving the valve stem. The upper half of the opening is of less diameter than the lower half so that this upper part will engage the circular groove 9 in the valve stem. A seat 10 is formed on the under face of the device for the upper end of the spring.

This device is particularly designed for use on tractors and motors which use very strong valve springs. The stem locks or washers of these springs soon wear out but with my device the wear is evenly distributed so that the device lasts for a long time. By making the device of two pieces hinged together it can be easily and quickly placed on the valve stem and removed therefrom. The spring holds it in place.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A spring retaining device comprising a pair of members hingedly connected together and each member having a semi-circular notch in its inner edge for receiving the valve stem, said notches having semi-annular shoulders for engaging the groove in the stem.

2. A valve stem lock comprising a pair of members hingedly connected together and each member having a semi-circular notch in its inner edge for receiving the valve stem, said notches having semi-annular shoulders for engaging the groove in the stem and a spring seat formed on the lower face of said members so that the pressure of the spring will hold said members on the stem.

In testimony whereof I affix my signature.

ROY E. WOLTKAMP.
